Inventor:

T. J. Sloan

United States Patent Office.

THOMAS J. SLOAN, OF NEW YORK, N. Y., ASSIGNOR TO EZRA GILDER-SLEEVE, OF THE SAME PLACE.

Letters Patent No. 63,317, dated March 26, 1867.

IMPROVED WINDOW-BLIND FASTENING.

The Schedule referred to in these Letters Patent and making part of the same.

TO ALL WHOM IT MAY CONCERN:

Be it known that I, THOMAS J. SLOAN, of the city, county, and State of New York, have invented a new and improved Mechanism for Opening, Closing, and Controlling Window Blinds and Shutters; and I do hereby declare that the following is a full, clear, and exact description thereof, reference being had to the accompanying drawings, making a part of this specification, in which—

Figure 1 is a rear elevation of the said mechanism as applied to a window frame and blind.

Figure 2, a vertical section taken in the plane of the line A a, fig. 1, with the blind thrown open.

Figure 3, a separate view of the handle for operating this mechanism; and

Figure 4, a face view of the locking-socket which holds the handle.

The same letters indicate like parts in all the figures.

Many attempts have been made to produce a means for opening, and closing, and fastening window blinds and shutters from the inside of the house and without opening the windows, but, so far as I am informed, without success until my said invention.

In the accompanying drawings, *a* represents one side of a window frame, and *b* a window blind represented as open in fig. 2, and *c* one part of the hinge, which said part consists of the hinge-pin or journal, and a shank which is to be secured to the outside of the window frame by screws or other equivalent means. The other part of the hinge *d* I prefer to make in the form of what is termed "angle-iron" that it may be secured by screws to the edge, and to one face of the blind or shutter as represented. And from this angle-piece an arm *e* extends out, and in under the face of this arm a socket is formed to fit and turn on the pin or journal of the part *c*. The blind or shutter turns on the hinge thus formed, and on another hinge of any suitable kind at the other end. The arm *e* is formed with bevelled cogs *f* in the form of a bevelled cog-wheel to engage the cogs of a bevelled wheel, *g*, on a horizontal shaft, *h*, which has one journal fitted to turn in a hole in the shank of the part *c* of the hinge, and at right angles to the axis of the pin, but in or nearly in the plane thereof. This shaft passes through the window frame *a* to the inside thereof, and through a plate, *i*, secured to the inner face of the window frame, which said plate serves the purpose of a box for the shaft to turn in. The inner end of the shaft is square to receive a handle or knob, *j*, fitted to slide thereon longitudinally, with a spring, *k*, interposed as represented. By turning the handle or knob *j* inside, the blind or shutter outside can be closed or opened to any extent; and for the purpose of locking it when either entirely opened or closed, the inner end of the hub of the knob *j* is formed with a tapered spur, *l*, which fits into a recess, *m*, in the face of the plate *i*, and the sides of this recess may also be bevelled, so that when the knob or handle is liberated after turning the shaft to either close or open the blind or shutter by the tension of the spring *k*, the spur *l* of the knob is forced into the recess *m* of the plate *i*, and as the sides of the spur are bevelled, when thus drawn into the recess, the shaft is turned to draw and hold the blind firmly, either when closed or opened, so that the wind cannot get behind to move it or make it rattle. A series of notches, *n*, are formed in the face of the plate *i* to receive the end of the spur *l* to hold the blind or shutter in any desired position between open and shut; and as in any of these positions the wind can exert considerable force on a blind or shutter, and in high winds breakage might result, the notches *n* are bevelled to allow the spur to slide out and permit the wind to either close or open the blind, but as the spur is forced into the said notches by the tension of the spring, and the wind cannot force the blind open or shut without overcoming the tension of the spring, it will follow that if the force be sufficient it will close or open the blind, but without violence. To prevent breakage, all that is necessary to be observed is to graduate the tension of the spring and the bevel of the notches to the strength of the blind and its connections, so that it will require less force to force the spur out of the notches than to break the blind or its connections.

What I claim as my invention, and desire to secure by Letters Patent, is—

The hinge having bevelled cogs, in combination with the shaft extending to the inside of the window, provided with a bevel cog-wheel, and the hinge-shank constituting the hinge journal on which the blind turns, and the box in which the shaft turns, substantially as and for the purpose described.

And I also claim the combination of the hinge with its bevelled cogs, the shaft with its bevelled cog-wheel, the spring spur on the knob, and the plate or its equivalent, with a recess to receive the spur to lock the blind when either shut or open, substantially as described.

And I also claim the bevelled recesses in the face of the locking plate, or the equivalent thereof for holding the blind or shutter at any angle desired, in combination with the spring spur, the shaft, and hinge connected by bevel gears, substantially as described.
